United States Patent Office.

GEORGE DICKERSON, OF HARVEYSBURG, OHIO.

Letters Patent No. 79,814, dated July 14, 1868.

IMPROVEMENT IN CORN-PLANTER.

The Schedule referred to in these Letters Patent and making part of the same.

TO ALL WHOM IT MAY CONCERN:

Be it known that I, GEORGE DICKERSON, of Harveysburg, Warren county, State of Ohio, have invented certain new and useful Improvements in Corn-Planters; and I do hereby declare the following to be a full, clear, and exact description thereof, reference being had to the accompanying drawings, making part of this specification.

My invention relates to that class of machines in which the seed-dropping mechanism is operated by one of the wheels of the machine, and consists in a peculiar construction and arrangement of devices for operating the seed-dropping slide, and in certain simple devices by which the covering-shares, the covering-roller, the sheath and seed-tube, are properly secured and adjusted. The entire machine is practically efficient, and is adapted for cheap and substantial manufacture.

In the accompanying drawings—

Figure 1 is a perspective view of a corn-planter, embodying my invention.

Figure 2 is a view of one of the wheels detached.

A is the beam, B the sheath, C the share, D D the covering-shares, E the covering-roller, F the hopper, G G' the handles, and H H' the wheels of the machine. The hopper F is provided with the customary slide I, brush J, and seed-tube K. The slide I is perforated at i, as shown, and is operated by means of the lever L, which is pivoted to the axle M, at m. The aperture i passes the brush, and seed is deposited in the tube twice to each revolution of the wheels H H', by the provision of the cams h h' on the wheel H, which are devised to move the lever L at each half turn of the wheels, and give the required throw to the seed-slide. The slide is returned after each deposit by the spring N.

The sheath and seed-tube are both confined to the beam by a single stay-bolt, P, the interior of the eye of which confines the tube, the exterior rigidly supporting the sheath. The covering-shares D D are hinged to the beam at d d', and diagonally supported and adjusted by the brace-bolts e e'.

The covering-roller E is hinged by the side-straps R R' to the beam at r r', and is adjusted in height by means of the bolt S.

I claim herein as new, and of my invention—

1. The general arrangement of the bracing and adjusting-bolts P e e' and S, sheath B, tube K, coverers D D, and roller E, all constructed and employed as described.
2. In combination with the above parts, I further claim the relative arrangement of the horizontal trigger L, retracting-spring N, and cam-wheel H h h', when constructed as specified.

In testimony of which invention, I hereunto set my hand.

GEORGE DICKERSON.
